UNITED STATES PATENT OFFICE.

ARTHUR L. GARFORD, OF ELYRIA, OHIO.

SEAT-POST FOR BICYCLES.

SPECIFICATION forming part of Letters Patent No. 578,399, dated March 9, 1897.

Application filed February 8, 1896. Serial No. 578,570. (No model.)

To all whom it may concern:

Be it known that I, ARTHUR L. GARFORD, a citizen of the United States, residing at Elyria, in the county of Lorain and State of Ohio, have invented certain new and useful Improvements in Seat-Posts for Bicycles; and I do hereby declare the following to be a full, clear, and exact description of the invention, such as will enable others skilled in the art to 5 o which it appertains to make and use the same.

My invention relates to improvements in so-called "direct" seat-posts for bicycles—that is, to seat-posts which include as part of themselves clamping mechanism for engagement with the saddle.

The object of the invention is to provide a simple, cheap, and effective device of this character; and the invention consists in the construction and combination of parts hereinafter described and claimed.

In the drawings, Figure 1 is a rear view of my improved seat-post in use with a saddle of which the frame is composed of two wires. Fig. 2 is a side view of the same, and Fig. 3 25 is a rear view of the seat-post in use with a saddle having that part of its frame which engages with the seat-post made of a flat spring.

Referring to the parts by letters, A represents the seat-post, which is approximately 30 cylindrical in form and is adapted to be secured in the usual socket provided therefor on bicycles.

At the upper end of the post are two laterally-movable clamping-jaws $a a$, having transverse grooves a' formed in their inner faces. These grooves are preferably curved so that they will conform to the usual shape of the saddle-frame member E, which lies in them. 35 A bolt C passes through both jaws, and it and its nut c are the means preferred for drawing said jaws toward each other.

When the saddle-frame member is composed of two parallel wires $e e$, a space-block 40 D is employed. It has grooves in its sides to receive the said wires, and on its under side is a perforated ear d. This space-block lies

between the wires $e e$ between the jaws, and the bolt C passes through the ear d and holds it in the described position.

When the saddle-frame member E is a flat spring, the post is used without the space-block.

In both cases the outer edges of the saddle-frame member lie in said grooves, and when 55 the jaws are drawn in the movement of said frame member is prevented.

The specific construction of the post, as shown in the drawings, is particularly light and cheap. The post is made of sheet metal, 60 steel being preferred, bent at its middle to bring the two legs $a^2 a^2$ into substantially parallel relation. Each of these legs is bent longitudinally into concavo-convex form, the concave faces being inside. Thus when the 65 two legs are in the described relation to one another the exterior configuration of the post is substantially cylindrical. The grooves $a' a'$ are formed by bending the upper or jaw portions of said legs between suitable dies. 70 The loop or bent part a^3 , which connects the two legs, acts to a certain extent as a spring, whereby said legs when not restrained by the bolt tend to move apart sufficiently to permit the saddle-frame member to be passed in and 75 out between the jaws.

Having described my invention, I claim—

A direct seat-post for bicycles consisting of two semicylindrical legs, the edges of which are adapted to contact, and a loop connecting 80 the lower ends of said legs, said parts being made integrally from the same piece of sheet metal, the legs near their upper ends being bent outwardly to form two interior transverse grooves a' , combined with a bolt which 85 passes through the upper ends of said legs and adapted to draw them together, substantially as and for the purpose specified.

In testimony whereof I affix my signature in presence of two witnesses.

ARTHUR L. GARFORD.
